UNITED STATES PATENT OFFICE.

WARREN W. BAIRD, OF AVALON, PENNSYLVANIA.

DESIGN FOR A SCOOP.

SPECIFICATION forming part of Design No. 32,387, dated March 27, 1900.

Application filed February 28, 1900. Serial No. 6,882. Term of patent 3¹ years.

To all whom it may concern:

Be it known that I, WARREN W. BAIRD, a citizen of the United States of America, residing at Avalon, in the county of Allegheny and State of Pennsylvania, have invented a certain new and useful Design for a Scoop, of which the following is a specification, reference being had therein to the accompanying drawings.

This invention relates to certain new and novel designs in scoops, and has for its object to provide a design of novel and original shape.

As shown in the accompanying drawings, the scoop consists of the novel outline and configuration which will be hereinafter more fully described and specifically pointed out.

In describing the invention in detail reference is had to the accompanying drawings, forming a part of this specification, and wherein like numerals of reference indicate corresponding parts throughout the several views, in which—

Figure 1 is a perspective view of my new and original design for a scoop. Fig. 2 is a cross-sectional view thereof.

Referring to the drawings by reference-numerals, 1 indicates a segmental-shaped piece of suitable material bent in a semicircular manner and having a U-shaped offset 2 formed integral with the top edge and arranged upon the outer face at the top thereof.

Having thus fully described my invention, what I claim as new, and desire to secure by Letters Patent, is—

The design for a scoop, substantially as herein shown and described.

In testimony whereof I affix my signature in the presence of two witnesses.

WARREN W. BAIRD.
